W. A. KUHLMAN

STRAP TIGHTENING AND HOLDING DEVICE

Filed Feb. 11, 1924

Patented Aug. 17, 1926.

UNITED STATES PATENT OFFICE.

WILLIAM A. KUHLMAN, OF TOLEDO, OHIO.

STRAP TIGHTENING AND HOLDING DEVICE.

Application filed February 11, 1924. Serial No. 691,988.

This invention relates to adjustable fasteners.

This invention has utility as a buckle or clamp for assembling and holding a binding strap or strip, as in assembling sections 5 for concrete forms.

Referring to the drawings:

Fig. 1 is a perspective view showing an embodiment of the invention as a buckle or 10 fastener for concrete forms;

Fig. 2 is a plan view, with parts broken away, of the buckle of Fig. 1 on an enlarged scale;

Fig. 3 is a side elevation of the buckle of 15 Fig. 2, parts being broken away; and

Fig. 4 is a medial section of the device.

In the assembly of forms for poured structures, as in connection with concrete, panels are built up generally to standard sizes to 20 respond to the general shape of the work to be formed. The columns may be round, polygonal or other shapes. In the instance shown herewith there is taken a rectangular shape. The panel is shown as comprising 25 boards 1 assembled by tie strips 2. These panels are assembled to define and hold the structure to be poured. As so grouped it is desirable to have these panels bound or clamped in assembled relation to resist or 30 hold up when the concrete is poured thereinto. Inasmuch as these forms are only left in position until the poured structure is sufficiently set and then removed, it is important that this removal may be had quickly 35 and conveniently. Furthermore, inasmuch, as these panels are re-used, it is desirable that the removal may not mutilate the panels. To this end the panels as herein disclosed are assembled by strips or straps 40 3, say of hoop iron, which may be of sixteen or eighteen gauge. In drawing this hoop iron about the group of panels it is desirable to have such iron brought to a taut 45 position as an effective holding, tightening, and clamping means.

The invention as herein disclosed comprises base or main member of a buckle or fastener. This base member is shown as having a plate 4 provided with a frame 5 rising therefrom, having a slot or opening 5' therein. In bringing this plate into use the hoop iron 3 has portion 6 bent back on itself to provide a loop 7 protruding through the opening 5'. Into this loop 7, a pin, as 55 an ordinary nail or spike 8, may be introduced. By having the end portion 6 of the

strip 3 on the under side or toward the panels as extending through the opening 5 and back along the panel, this end 6 is clamped by the under side of the strap 60 against the panel and there is minimized any tendency of this end of the strip to work loose from the base 4.

Rising from this plate 4 of the main base is a pair of brackets 9 merging toward the 65 frame 5. These brackets have bearing-providing openings 10 in alignment. A pin 11 is provided with a slot 12 through which may extend end portion 13. As threaded 70 through the slot 12, this end portion 13 may even protrude through the slot 12 to have bent over portion 14. This threading of the end of the strap 3 into the slot 12 of the pin 11 may be as the pin 11 is thrust from one opening 10 to the other or after the pin 11 has been inserted in both openings 10 75 as rising from the plate 4. When so assembled and with this end 13 of the strap 3 threaded therewith, the pin 11 may have its square head 15 engaged by a wrench or 80 other tool, and turned to wind the strap 3 into taut condition for effectively clamping or binding the column panels in assembled relation. The pin 11 may be keyed 85 against removal from the base by nail 16 90 or other pin fastener through opening 17 to thereby serve as a key. In the winding of this strip 3 about the pin 11, if such winding be over the pin 11 instead of under, there is more positive holding action for 95 this fastener into snug position against the panel. Openings 18 in the head 15 may receive pin or nail 19 of a length to engage the base 4 and hold the pin from unwinding. The nail 16 may be of such length 95 as not only to be used as key but to serve to prevent unwinding of the pin 11 by engaging the plate 4.

In the tightening of the strap 3 there is 100 in many instances requirement for rather close clamping adjustment to be obtained with speed. To this end the head 15 of the pin 11 is provided with a ratchet portion 20 with which may be engaged by pawl 21 having trunnion 22 extending through opening 105 23 in one of the brackets 9. The operator may place a finger on the pawl as the pin is being set up to urge the pawl into a ratchet seat. By this means there is close angular adjustment over a wide range for this pin 11. 110 The trunnion 22 is of such size that by a stroke from a hammer it may be sent into

position one side up in one bracket 9 for one way of holding the pin 11, and into the other bracket 9 for the other way of holding the reversed pin 11.

5 The fastener may have the respective connections through opening 24 instead of the opening 5 with the key, pin or nail held in openings 25; while the lead into the pin 11 of the strip 3 may be through the opening 10 26. This means that in the connections to this device such may be at a corner or even through slot or opening bridged by this device.

15 This fastener may serve as a panel assembly for forms other than columns. Girder panels 27 have their open top portions spaced by braces 28 and the strap 3 with this base 4, 9, 10 and 11 connected for clamp assembly of such girder forms.

20 When the concrete has been poured into the structure and sufficient time has elapsed for the desired set, it is only necessary for the workmen to come to the device of this disclosure, knock out nails 8 and the device is at once free, as the strap 3 is thus loosened from the panels. The strap 3 may be discarded or it may be re-used as its condition may warrant. It is thus seen that there is disclosed herein a simple, effective, 25 and substantial fastener of ample tightening capacity which is capable of time saving use in assembling and knocking down forms in connection with poured structures.

30 What is claimed and it is desired to secure by Letters Patent is:—

35 1. Strap tightening and holding means including a base providing a plate portion

having a slot for receiving a strap end as looped back therethrough, a pair of uprising brackets from said plate providing a seat, 40 a withdrawable holding pin through said looped strap end held in said seat by the strap, said brackets providing bearings and a pin rotatably mounted in said bearings for engaging the opposite end of the strap. 45

2. Strap tightening and holding means including a base, a pin reversible end for end in said base for winding in different directions as to said base, said pin having a seat for receiving a strap end, said base having bearings for said pin, and checking means removably mountable with said base for swinging into pin engaging position, said base providing one seat for the checking means with the pin mounted for one direction of winding and a second seat for the checking means when the pin is mounted for the reverse direction of winding. 50

3. Strap tightening and holding means including a mounting unit comprising a 60 base plate and a pair of opposing upstanding brackets, said unit having a slot for the looped end of a strap, a pair of seats adjacent said slot, a rod through the looped end resting in said seats, there being seats in the brackets parallel to said rod, a pin rotatably mounted in the bracket seats for engaging the other end of the strap, a ratchet fixed to the pin, and ratchet engaging means pivotally mounted on the bracket 65 of said unit toward the base plate from said pin and between said pin and rod. 70

In witness whereof I affix my signature.
WILLIAM A. KUHLMAN.
